United States Patent Office

Des. 182,080
Patented Feb. 11, 1958

182,080

WINDOW OPERATOR

John R. Morgan, Northbrook, Ill., assignor to Amerock
Corporation, Rockford, Ill., a corporation of Illinois

Application April 4, 1957, Serial No. 45,594

Term of patent 14 years

(Cl. D10—10)

Fig. 1

Fig. 2

Fig. 3

Figure 1 is a perspective view of a window operator showing my new design.

Fig. 2 is a sectional view taken along the line 2-2 in Fig. 3.

Fig. 3 is an enlarged fragmentary plan view of the operator.

Fig. 4 is a fragmentary side view.

Fig. 5 is an enlarged fragmentary plan view of the handle portion of the operator.

Fig. 6 is an end view of the handle portion.

Fig. 7 is a fragmentary sectional view taken along the line 7-7 in Fig. 3.

Fig. 8 is a sectional view taken along the line 8-8 in Fig. 3.

I claim:

The ornamental design for a window operator substantially as shown.
